RAGLAN SLEEVE GARMENT

Richard E. Blood, Amsterdam, N. Y.

Application February 24, 1937, Serial No. 127,549

2 Claims. (Cl. 2—125)

This invention relates to improvements in wearing apparel, and particularly to garments such as shirts and coats of the raglan sleeve style.

Primarily, the object of the invention is to simplify the fabrication of garments of this type of standard measurements and to minimize the cost of production of such garments by saving in material or total pattern surface.

More particularly, the invention contemplates the production of garments having raglan sleeves and body portions having either straight or shaped sides, gussets or inserts being used to give fullness to the sleeves and to the body of the garment when the latter has shaped sides. To minimize the quantity of material used in providing these gussets, the sleeves of the garment are cut from a blank of fabric, usually of two plies, and the necessary gussets preferably formed by cutting the blank at the cuff-end of the sleeve to form a cuff of reduced diameter, although additional gussets which are required for the shaped-side garment may be cut from a separate piece of goods.

With these and other objects in view, the invention consists in certain details of construction and combinations and arrangements of parts, all as will hereinafter be more fully described and the novel features thereof particularly pointed out in the appended claims.

30 In the accompanying drawing—

Figure 1 is a plan view, more or less diagrammatical, illustrating a so-called blank from which the body portions of two garments are cut;

Fig. 2 is a like view of a blank from which the sleeves and gussets for two straight-side garments are produced;

Fig. 3 is a front elevation of a straight-side garment, including the sleeves and gussets;

Fig. 4 is a like view of a shaped-side garment;

40 Fig. 5 is a more or less diagrammatical view of a separate blank of material from which gussets may be formed; and

Fig. 6 is a plan view of a pair of gussets used for an insert in the shaped-side garment.

45 The body portions of the garment—shirts in the present illustration—are preferably cut from blanks such as illustrated in Fig. 1, and the sleeves from a blank such as illustrated in Fig. 2. This is true, whether the body of the finished garment is to have straight or shaped sides. In cutting out the bodies, the so-called blank is formed by folding a piece of material upon itself along the edge 10, the length of the material corresponding to the over-all length of two garments. The material is then cut along lines 12, 13, converging

inwardly from the two side edges 10, 11, so that by sewing the two plies of material together along the edge 11, two tubular body portions will be produced, each having one straight end and one end with two V-shaped recesses 5 therein at what would otherwise constitute the shoulder portion of the garment. To impart better shape to the neck line, the goods may also be cut along lines 14. For garments with straight-sided bodies, the goods should be cut 10 about three inches along lines 15 from each point "X" in the direction of the arrows and for shaped-side garments this cut should extend about ten inches, for accommodation or attachment of inserts, as will presently be described.

15 In cutting out the sleeves, a similarly plied piece of goods (Fig. 2) of a length equal to two sleeves, is cut inwardly from its edges 16, 17 along converging lines 18, 19, the points at which said lines intersect each other and the side edges of 20 the blank being equidistantly spaced from the longitudinally medial point of the blank. At one end of the blank, the material is cut along lines 20, 21, to form cuff portions of reduced diameter and the material at the opposite end is cut along 25 its longitudinal center, as indicated by line 22, and also along lines 20^a, 21^a, to form reduced cuff portions on the sleeves. When cut as thus described, the piece of material, indicated at "A" of each ply, will form a sleeve when sewed along 30 its free edges and each two portions "B" of the two plies will likewise form a sleeve, making four sleeves in all cut from the blank. As will be apparent, by cutting the material along lines 20, 21 and 20^a, 21^a to form the reduced cuff portions of the sleeves, material for four substantially V-shaped pieces or gussets, indicated at 35 23, will be produced, and it is these gussets that are utilized in giving fullness to the sleeves in the finished garment, thus eliminating all waste of 40 material in the production of the garment. For instance, in the straight-sided garment illustrated in Fig. 3, the tapered ends of the sleeves are set into the recessed portions of the body and form the shoulder portion thereof, the edges 45 of the sleeves formed by lines 18, 19, being stitched to the edges formed by lines 12, 13, along which the body portion was cut from the original blank. A gusset 23 is then inserted in each arm-pit of the garment with its apex disposed away from 50 the arm-pit. In other words, the edge of the gusset opposite its apex is attached to the edges formed by the cuts along lines 15 in the blank and the edges of the gusset defined by the lines 20, 21 or 20^a, 21^a, are attached to edges of the 55

sleeve proper which, of course, have not been sewn together their entire length toward the arm-pit.

In fabricating the shaped-side garment illustrated in Fig. 4, the bodies and sleeves thereof are cut from blanks of material just as they are for the straight-sided garment, but as previously mentioned, the bodies are slit along lines 15 (Fig. 1) about ten inches. Also, in order to shape the 10 side of the garment to more neatly fit the body of the wearer, two gussets are combined to form the insert under the arm-pit. For this reason, it is necessary to cut additional gussets from a separate piece of material, as shown in Fig. 5 because only two gussets are provided from the 15 blank of Fig. 2 for each pair of sleeves cut therefrom. These additional gussets are preferably cutout from a double-ply blank, the blank being cut along the lines 30, 30^a, and 31, 31^a, and transversely on the lines 40, 41, thus producing eight 20 gussets. It will be observed that cutting the blank of Fig. 5 along the offset lines 40, 41, produces a gusset having its edge opposite its apex recessed or dished. Such a gusset is illustrated 25 at 23^a in Fig. 6. On the other hand, the material of the blank of Fig. 5 is also cut at its corners along the lines 50, thus forming each of four of the gussets from said blank with a raised portion on its edge opposite its apex, as shown at 23^b in 30 Fig. 6. Thus, two gussets such as 23^a, 23^b can be neatly fitted together along their edges opposite their apices to produce the insert shown at the arm-pits of the garment illustrated in Fig. 4. As will be understood, the longitudinal edges of 35 these inserts are secured to the edges of the under unseamed portions of the sleeves of the garment and to the edges of the material formed by the slits 15 in the garment body. With the two gussets forming the insert neatly mated or 40 fitted together and the insert secured in the arm-pit with the apices of the two gussets disposed away from the arm-pit or downward portion, so to speak, of the sleeve and body, a well-fashioned or shaped side is produced in the finished garment. At the same time, there is practically no 45

loss of material in cutting out the several units of which each garment is constructed, and all of said units are formed with a minimum number of cuts and in a very simple and efficient manner.

It should be added that where the gussets cut 5 from the blank of Fig. 2 are to be used in a shaped-side garment, the gusset-forming portions of the material can be cut along the lines (shown dotted) 40^a, 50^a, to produce two pairs of mating gussets 23^a, 23^b.

In both types of garments, the inserts, whether formed of one or two gussets, give the fullness in the fit of the garment, as is desirable in the raglan sleeve style of garment and, as previously pointed out, all the constituent parts of the garment are 15 formed or cut out without waste of material.

What I claim is:

1. The method of fabricating a raglan-sleeved garment such as a shirt which comprises preparing a two-ply blank of material, cutting said blank along converging lines extending inwardly from the side edges of said blank, said lines extending from a point at one side of the longitudinally medial point of the blank and intersecting at the longitudinal center of the blank at the 25 other side of said medial point to form the shoulder portions of the garment sleeves, cutting substantially V-shaped pieces from each end of said blank to form reduced cuff portions for said sleeves, attaching the shoulder portions of the 30 sleeves in a garment body, and securing said V-shaped pieces in the arm-pits of the garment with the apices of said pieces disposed away from the arm-pit.

2. The method of fabricating a raglan-sleeved 35 garment such as a shirt which comprises cutting substantially V-shaped pieces of material from the cuff end of material blanks constituting the sleeves of the garment to form sleeves having reduced cuff portions, attaching the shoulder portions of the garment sleeves in the garment body, and securing said V-shaped pieces in the arm-pits of the garment with the apices of said pieces disposed away from the arm-pits.

RICHARD E. BLOOD.
